United States Patent Office

Des. 187,926
Patented May 17, 1960

187,926

HEARING AID

Melvin H. Boldt, Glenview, Ill., assignor to Zenith Radio Corporation, a corporation of Delaware

Application December 4, 1959, Serial No. 58,558

Term of patent 14 years

(Cl. D26—14)

FIG. 2

FIG. 1

FIG. 3

FIG. 4

Figure 1 is a front elevational view of my design for a hearing aid;

Figure 2 is a left side elevational view thereof;

Figure 3 is a right side elevational view thereof; and
Figure 4 is a top view thereof.

The bottom and back are plain and unornamented.

I claim:

The ornamental design for a hearing aid, substantially as shown and described.
